[57] **ABSTRACT**

A process for the preparation of a sample to be tested by immunological assay for detecting serum gonadotrophin in blood of mares, for the purpose of diagnosing the mares pregnancy, which comprises adding an acid selected from the group consisting of sul-fosalicyclic, perchloric, and metaphosphoric acids, to the blood, plasma, or serum of the mare to be diagnosed, at a concentration of at least 0.15 m-mol based on 1 ml of serum but below the saturation concentration, separating the resultant precipitate and recovering the supernatant liquid, and a method diagnosis of pregnancy of a mare using such test sample.

1 Claim, No Drawings

**PREPARATION OF TEST SAMPLE FOR
IMMUNOLOGICAL ASSAY OF PREGNANCY OF
MARES.**

This invention relates to an improved process for making the sample to be tested (hereinafter called "test sample") for diagnosing pregnancy of mares by immunological assaying of gonadotrophin contained in the blood, plasma or serum of pregnant mares. The invention furthermore relates to an improved method for diagnosing pregnancy of mares, and also to the set of chemicals for diagnosing pregnancy of mares.

A pregnant mare, secretes pregnant mare serum gonadotrophin (hereinafter to be abbreviated as PMS), which is one of the glycoproteins, from placenta. This hormone becomes observable in the mare's blood approximately thirty days after fecundation, and its concentration in the blood reaches the maximum during the period of approximately 40 - 90 days after fecundation. Therefore an assay of PMS in mare's blood enables early diagnosis of pregnancy. This method has been considered to be the most reliable diagnostic method for that purpose, but is subject to such a drawback that it is too complex for clinical diagnosis, because the necessity for utilizing biological activity of PMS requires living laboratory animals.

Recently, however, a method for assaying PMS by an immunological means was discovered, and thereby an easy assaying in short period became possible. However, by that method a correct diagnosis is difficult if the blood, plasma, or serum of a mare is used as the test sample as it is, because the same contain blood components which interfere with the assaying reaction (presumably the proteinous components other than PMS) at high concentrations and consequently the accuracy of the reaction is impaired. In order to avoid such inaccuracy, it was proposed to isolate serum from the blood to be assayed, and to use the serum, which is subsequently diluted to the critical concentration to eliminate the action of objectionable components, for example, proteins, as the test sample. Also, as an alternative, it is known to add an organic solvent such as alcohol or acetone to the serum to precipitate PMS, and to use as the test sample the extract obtained by extracting the precipitate with isotonic sodium chloride solution. However, in the former method the correctly positive reaction result may not be obtained due to low PMS content in the test sample, since the PMS concentration in the sample also is reduced by the dilution. Whereas, the latter method is unsuitable for clinical use since it involves complex procedures.

It has now been discovered that, among the various protein precipitation or deproteinizing agents, particularly sulfosalicylic acid, perchloric acid, and metaphosphoric acid give favorable results. That is, when such an acid is added to blood, plasma or serum of a pregnant mare (hereinafter the substances will be collectively referred to as the serum) at a specific concentration, the blood components interfering with the haemagglutination inhibition reaction of gonadotrophin in the serum, such as proteins, can be selectively precipitated, without affecting the gonadotrophin. It has furthermore been discovered that such a test sample for diagnosis of pregnant mare utilizing the haemagglutination inhibition reaction of PMS can be prepared with simple operation, without diluting the serum.

Accordingly, therefore, an object of the invention is to provide a process for the preparation of test sample for diagnosis of pregnant mare by means of haemagglutination inhibition reaction of PMS, which can be easily practiced by a veterinary surgeon on the spot.

Another object of the invention is to provide a process for the preparation of test sample which is valuable for diagnosis of pregnant mare by means of haemagglutination inhibition reaction of PMS, which enables determination of mare's pregnancy with very high reliability.

Still another object of the invention is to provide an improved method of diagnosis of pregnant mare by means of haemagglutination inhibition reaction of PMS, which enables veterinary surgeons to determine if the mare is pregnant with ease and high reliability at the spot of diagnosis, and also to provide as set of diagnostic chemicals to be used in that method of diagnosis.

The foregoing objects of the invention are accomplished by the process for the preparation of sample to be tested by immunological assay for detecting serum gonadotrophin in blood of mares, for the purpose of diagnosing the mare's pregnancy, which comprises adding an acid selected from the group consisting of sulfosalicylic, perchloric, and metaphosphoric acids, to the blood, plasma or serum of the mare to be diagnosed, at a concentration of at least 0.15 m-mol based on 1 ml of the serum but below the saturation concentration, separating the resultant precipitate and recovering the supernatant liquid.

In accordance with the invention, the blood, plasma or serum of the mare to be diagnosed can be used. For taking blood from the mare, it is important to select the period during which the PMS concentration in the mare's blood reaches its maximum, in order to improve the accuracy of diagnosis. As aforesaid, the highest concentration is normally obtained during approximately 40 to 90 days after fecundation. Accordingly, in accordance with the invention it is preferred to use blood, plasma or serum of a mare, taken on the 40th to 80th day from the last mating. It is of course possible to use blood, plasma or serum of a mare taken on the 30th to 40th day from mating, if an early diagnosis is aimed at. However, since the reliability of the diagnosis in that case is somewhat impaired, a re-diagnosis at a later date may be required. The amount of blood required is preferably 2 - 10 ml per one diagnosis, for easy operation.

According to the invention, an acid selected from the group consisting of sulfosalicylic, perchloric and metaphosphoric acids is added to the mare's blood, plasma or serum, at a concentration of at least 0.15 m-mol based on 1 ml of serum, but below saturation point. With the addition of such a specific acid in the specific amount, it is possible to selectively precipitate the blood components interfering with the haemagglutination inhibition reaction of gonadotrophin, such as proteins other than PMS, without precipitating the PMS contained in the serum.

It has been known that addition of an organic acid such as trichloroacetic, sulfosalicylic, picric, or tannic acid; an inorganic acid such as phosphotungstic, phosphomolybdic, tungstic, and metaphosphoric acid; or a heavy metal salt such as zinc chloride, copper sulfate, lead acetate, Reinecke's salt, etc. to an aqueous

solution of proteinous substance is useful for precipitation of the proteinous substance. However, it has been discovered that, among the above many deproteinizing agents, particularly sulfosalicylic, perchloric, and metaphosphoric acids only can selective precipitate the objectionable components (i.e. proteins other than PMS), without affecting PMS, at relatively wide concentration ranges. In fact, deproteinizing agents outside the scope of this invention are unsatisfactory in that either they precipitate PMS and the objectionable components simultaneously, or cannot effectively precipitate the objectionable components. Furthermore, for some deproteinizing agents which exhibit neither of the above objectionable activities, the effective concentration range is extremely narrow and clinically impracticable.

The above statement is substantiated by the data given in Table 1 below, which are obtained by subjecting test bodies, prepared by adding various deproteinizing agents to a pregnant mare's serum at various concentrations, to a haemagglutination inhibition reaction test.

METHOD OF TESTING

Each 2 ml of a non-pregnant mare's serum, and of the same serum in which 12 international units of PMS per 1 ml of the serum had been dissolved, were taken into small test tubes, and to each of the tubes 2 ml of the deproteinizing reagent solution of the concentration given in the table were added, followed by thorough agitation. Each sample was then centrifuged for 30 minutes at a rate of approximately 3,000 rpm. The coagulated protein was precipitated and removed. The transparent or slightly turbid supernatant liquid

was taken with a pipette, and neutralized to pH 5.0 - 8.5 with N.NaOH. The prepared test samples were subjected to the haemagglutination inhibition reaction test in the following manner.

5 Into a small test tube of approximately 1 cm in diameter, 0.3 ml of a diluted solution of an antiserum which will be fully explained later was taken, and to which 0.1 ml of the test sample and a drop (approximately 0.07 ml) of PMS-sensitized blood cell suspension (which will be specified later) were added, well shaken and allowed to stand. After allowing to stand for approximately 2 hours, the bottom of the test tube was observed. When PMS was present in the test sample as dissolved in the serum, the PMS and the antibody were bound, but bonding of PMS-sensitized blood cells with the antiserum, i.e., agglutination of blood cells was inhibited, and consequently the blood cells were precipitated, forming a ring. In contrast thereto, when PMS was absent in the test sample, the agglutination of PMS-sensitized blood cells was not inhibited, and consequently a uniform mat covering the entire bottom of the test tube was formed.

10 15 20 25 30 35 Table 1 given below shows the results of above experiments, in which the evaluation of + is given to clearly ring-formed precipitate, $\pm$ is given to ambiguously ring-formed precipitate, and - to the mat-like precipitate. Also in the column on properties of supernatant liquid, the protein concentration was determined by Lowry's reaction (Lowry, O.H., N.J. Rasebrough, A.L. Farrand & R.I. Randall; J. Biol. Chem. 193, 265, 1951), and expressed by absorbance at a wavelength of 750 m μ . The concentrations marked with * sign were those in the supernatant liquids of which pH was controlled with N. HCl after addition of the reagent solution.

TABLE 1

Deproteinizing reagent	Properties of supernatant liquid			Reaction			
	Type	Concen- tration	Color	pH	Protein con- centration	Serum con- taining PMS	Serum con- taining no PMS
Sulfosalicylic acid	1.2 M	Slightly turbid		0.3	1,390	+	-

hibition reaction of PMS can be easily obtained. In fact, in accordance with the invention, the necessary operation of a veterinary surgeon for the preparation of test sample is no more than the addition of an equal amount of deproteinizing agent solution to the mare's serum and removal of the resultant precipitate from the system.

The obtained supernatant liquid is acidic due to the deproteinizing agent employed, which can be optionally neutralized with a caustic alkali solution. In that case, normally IN caustic soda aqueous solution is conveniently used. In the neutralizing procedure, a pH indicator may be added previously into the reagent for precise indication of neutralization point, to facilitate an easy and accurate pH control of the supernatant liquid, for example, pH 5 to 8.5. As such an indicator, p-nitrophenol is preferably recommended.

The supernatant liquid as the test sample is then subjected to the known haemagglutination inhibition reaction test. The amount of the test sample required for this test is in the order of 0.1 ml.

Furthermore, the invention provides a method of diagnosis of pregnancy of mares comprising mixing a test sample containing PMS but containing substantially no proteinous impurities, with antiserum against PMS, mixing the resultant solution with PMS-sensitized blood cells, and allowing the solution to stand to perform the haemagglutination inhibition reaction test, which is characterized in that the test sample is obtained by the steps of adding an acid selected from the group consisting of sulfosalicylic, perchloric and metaphosphoric acids to blood, plasma or serum of the mare to be diagnosed, at a concentration ranging from 0.15 m-mol based on 1 ml of serum to the saturation concentration, separating the precipitate formed and recovering the supernatant liquid, and neutralizing the same with an alkali to a pH ranging from 3 - 9.5, particularly 5 - 8.5.

The PMS-sensitized blood cells to be used in the haemagglutination inhibition reaction test is a substance itself known. It can be prepared, for example, by the method disclosed in Nature, Vol. 198. p. 1017 (1963).

In one embodiment, a fixing agent such as formaldehyde, pyruvic aldehyde, glutaraldehyde, or hydrogen peroxide, is added to a suspension of sheep's erythrocytes, followed by incubation to fix the erythrocytes. The fixed erythrocytes are then treated with tannic acid or bis-diazotized benzidine, and to which a PMS solution is added to sensitize the erythrocytes with PMS.

A specific example of preparing PMS-sensitized blood cells will be given hereinbelow.

EXAMPLE A

Erythrocytes of a sheep are thoroughly washed with isotonic sodium chloride solution, and thereafter formed into a 8 percent erythrocyte suspension. To the suspension an equal amount thereto of 3 percent formalin is added, followed by heating to 37° C. for approximately 24 hours to fix the erythrocytes. The fixed erythrocytes are washed and suspended in phosphoric acid buffer solution at a concentration of 8 percent. An equal amount of 1/20,000 tannic acid solution is added to the suspension, and the system is heated to 57° C. for 30 minutes, followed by washing with phosphoric acid buffer solution. The system is then suspended in the same buffer solution at a concentration of 8 percent.

To the suspension, then 100 IU/ml of PMS solution is added, followed by 2 hours' heating at 56° C. to complete PMS-sensitization. The system is finally washed with phosphoric acid buffer solution and is made into 2.5 percent PMS-sensitized erythrocyte suspension.

The obtained PMS-sensitized blood cell suspension can be stored in a cold place as it is, and optionally taken out for actual use. However, it is preferred for clinical use to keep it in the form of frozen and dried, powder product.

As already mentioned, only a drop (approximately 0.07 ml) of this PMS-sensitized blood cell suspension is required in one test. The suspension of the amount necessary for one to several tests can be enclosed in an ampule for convenient use by veterinary surgeons, together with an inert solid carrier, for example, a saccharide such as lactose, sucrose, sorbitol, etc. and frozen and dried.

The antiserum against PMS, which is employed in the invention, is again a know substance itself, and can be prepared by the means known per se. The preparation method again is described in the aforesaid Nature, Vol. 198, p. 1017 (1963).

EXAMPLE B

For example, 2,000 - 5,000 IU/ml of PMS solution is mixed with an equal amount of an adjuvant, such as Romon's or Freund's adjuvant. Then a mature rabbit is immunized by hypodermic injection of the mixture obtained in the above, three to four times every other week. The rabbit blood is extracted and the serum therefrom, is separated, and the antiserum against PMS can be obtained.

It is preferred to use the antiserum obtained as in the above in an amount as much as 1.5 - 4 times the corresponding amount to PMS-sensitized blood cells. For this purpose, the rabbit's antiserum against PMS is multiply diluted with phosphoric acid buffer solution to form various multiply diluted solutions, and each 0.3 ml of the dilute solutions is taken into a small test tube. Into each test tube then a drop (approximately 0.07 ml) of the PMS-sensitized blood cell suspension is added, and the system is well shaken and left to stand for approximately 2 hours. Then the state of the aggregate formed at the bottom of test tube is observed. If evenly spread precipitates covering the entire bottom of the tube are observed, the state is judged to be "agglutination", and when red, ring-formed precipitates are observed, the judgment of "non-agglutination" is given. Thus the maximum value of diluting multiple samples of the antiserum showing the perfect agglutination is determined, and 1/1.5 - 1/4 of the maximum value of diluting multiple samples is used as the antiserum concentration corresponding to the PMS-sensitized blood cell suspension employed in the experiment. Then the dilute solution having the so determined concentration is referred to as dilute solution of the antiserum.

This dilute solution of the antiserum can be stored in a cold place as it is, and optionally taken out at the required occasion. However, for convenient clinical application, it is preferred to insert the necessary amount of the dilute solution of the antiserum for single time usage, i.e., 0.3 ml, into an ampule together with an inert solid carrier, for example, saccharides such as lactose, sorbitol, etc., or an amino acid such as glycine,

sodium glutamate, etc., followed by freezing and drying.

The diagnosis on pregnancy of mare utilizing the haemagglutination inhibition reaction of PMS is performed as follows:

0.3 ml of the dilute solution of the antiserum is placed in a small test tube, 0.1 ml of the test sample and a drop of the PMS-sensitized blood cell suspension are added to the test tube, the mixture is shaken well, and is allowed to stand for approximately 2 hours. Then the inside bottom of the test tube is observed. When the test sample contains PMS dissolved therein, the PMS and antibody are bound and thereby the bonding of PMS-sensitized blood cells with the antiserum, i.e. agglutination of blood cells is prohibited. Accordingly the blood cells are precipitated in the form of a ring. In contrast, if the test sample no contains PMS, the agglutination of PMS-sensitized blood cells is not inhibited, and consequently an evenly precipitated blood cell aggregation is observed at the bottom of the test tube. PMS can be thus detected by the foregoing method. Also when determination of PMS is necessary, the test sample is multiply diluted, and the quantity of PMS is calculated from the maximum dilution ratio.

When the frozen and dried products of antiserum and PMS-sensitized blood cells are used, the following procedures are followed: 0.1 ml of the test sample is added to the antiserum powder in the ampule, to dissolve the latter. Separately, 1 ml of a buffer solution of pH 5 - 9, inter alia, 6 - 8, is added to the PMS-sensitized blood cell powder in the ampule, to form the suspension of the PMS-sensitized blood cells. Then 0.2 - 0.4 ml of this suspension is added to the test sample containing the antiserum dissolved therein.

In assaying PMS by means of the haemagglutination inhibition reaction as mentioned above, if the blood or the serum as extracted from a mare is used as the test sample, certain components in the blood inhibit the agglutination of PMS-sensitized blood cells. Consequently the blood cells are precipitated in a ring form even when the test sample is taken from a non-pregnant mare and no contains PMS, showing a positive reaction result. This inevitably invites erroneous diagnosis. However, in accordance with the present invention, the components causing such inconveniences are sufficiently removed from the test sample by the deproteinizing reagent specified in the foregoing. Accordingly, very accurate diagnosis on pregnancy of mare can be given, suing the supernatant liquid, which is separated from the objectionable components, as the test sample.

The reagents to be employed in the subject method of diagnosis are preferably prepared in the form of a set, for convenient use by clinical veterinary surgeons.

This invention also provides a set of diagnostic chemicals for pregnancy diagnosis of a mare of 60 haemagglutination inhibition reaction of gonadotrophin in blood, plasma or serum of a pregnant mare, which comprises an antiserum against PMS, and PMS-sensitized blood cells which are prepared by the steps of fixing blood cells with a fixing agent selected from the group consisting of formaldehyde, pyruvic aldehyde, glutaraldehyde and hydrogen peroxide, treating the fixed blood cells with an agent selected from the group consisting of tannic acid and bis-diazotized benzidine, and sensitizing the same with PMS, the set

characteristically comprising a deproteinizing agent consisting of an aqueous solution of an acid selected from the group consisting of sulfosalicylic acid and perchloric acid, of a concentration ranging from 0.15 mol to saturated concentration.

The above-specified set can optionally include an aqueous solution of a caustic alkali such as caustic soda or caustic potash, at a concentration of 0.5 - 5N, as a neutralizing agent of the acid. Also when frozen-dried powder of PMS-sensitized blood cells is used, a buffer solution of pH 5 - 9, a, preferably 6 - 8, can be included in the set for dissolving the powder.

EXAMPLE 1

A set of the following diagnostic chemicals was prepared:

A tube:

Frozen and dried product, 0.3 ml of the antiserum dilute solution prepared in accordance with Example B, put in an ampule together with 3 mg of lactose;

B tube:

Frozen and dried product, 0.35 ml of PMS-sensitized blood cell suspension obtained in Example A, placed in an ampule together with 20 mg of sucrose;

C tube:

1.0 ml of a buffer solution, such as those described below, inserted in an ampule;

Types of buffer solutions

1. Phosphoric acid buffer solution

Per ml of the solution:

Sodium hydrogenphosphate (Na_2HPO_4) 3.72 mg

Potassium dihydrogenphosphate (KH_2PO_4) 6.64 mg

Sodium chloride ($NaCl$) 4.50 mg

pH 6.4

2. Boric acid buffer solution

Per ml of the solution:

Boric acid (H_3BO_3) 4.4 mg

Sodium borate ($Na_2B_4O_7 \cdot 10H_2O$) 3.0 mg

Sodium chloride ($NaCl$) 7.6 mg

pH 8.2 - 8.3

3. Citric acid buffer solution

Per ml of the solution:

Citric acid ($C_6H_8(OH)(COOH)_3$) 11.13 mg

Potassium hydroxide (KOH) 8.53 mg

pH 6.4

D tube:

2 ml of 0.3 mol concentration solution of sulfosalicylic acid, inserted in an ampule;

E tube:

0.5 ml of 1N-sodium hydroxide solution inserted in an ampule.

Usage of the set:

1 4 ml of blood, or 2.0 ml of plasma or serum was extracted from a 6 yrs. old percheron mare 49 days after mating and put into a centrifugal precipitation tube. 2.0 ml of the deproteinizing agent in D tube was added into the precipitation tube, and the content was stirred thoroughly with a glass rod, followed by centrifuging. Then the supernatant liquid was separated.

2 1.0 Milli-liter of the supernatant liquid of 1 was placed in a test tube and neutralized with 5 - 6 drops of the neutralizing agent in E tube.

- 3 0.1 Milli-liter of the neutralized test sample of (2) was added into A tube to dissolve the antiserum.
- 4 1.0 Milli-liter of the phosphoric acid buffer solution in C tube was added into B tube to make a PMS-sensitized blood cell suspension.
5. 0.2 Milli-liter of the sensitized blood cell suspension of (4) was added to A tube of (3), well shaken, and left to stand on a rack.
6. After approximately 2 hours' standing, the state of aggregate formed on the bottom of A tube was observed for the diagnosis.

As the result, no agglutination of blood cells was observed, but the erythrocytes sedimented in a ring form was observed.

The same test was given to 113 test samples taken from pregnant mares on the 45th to 80th days after mating, with correctly the positive reaction results. The accuracy of the diagnosis was 95.9 percent. Also when the test was performed as to 33 non-pregnant mares, the results were negative with 100 percent accuracy.

EXAMPLE 2

Each 2 ml of serums of pregnant and non-pregnant mares were placed in small test tubes, and added with 2 ml of 0.35 M perchloric acid solution. After thorough shaking, the test tubes were either subjected to a centrifuge at a rate of approximately 3,000 r.p.m. for 10 minutes, or left standing in a refrigerator for at least three hours. Whereupon the coagulated proteins were precipitated. The supernatant liquids or slightly turbid

the similar testing procedures as in the above, all the test samples exhibited positive reaction results.

EXAMPLE 4

- 5 Using the set of diagnostic chemicals specified in Example 1, assay was similarly performed on the test samples of the mares' serums taken on various dates from mating. The results were as given in the table below. Thus the positive reaction appeared in the test samples 10 from the serums extracted from the mares on the 39th to 46th days after mating. The positive reaction of the test samples continued until 71 - 104 days after fecundation of the mares.

Pedigree	Age	Fooling record	Days after last mating
			and results of immunoassay
Percheron	6	0	19 28 39 49 58 69 79 100 129 - + + + + + ±

25

Example 5

- Using the set of diagnostic chemicals specified in Example 1, assay was similarly performed on test samples prepared from serums of various mares, with the results 30 as given in the table below. The serums taken on the 45th - 80th day after mating showed the highest level of positive reaction. Also light mares exhibited higher level of positive reaction than heavy mares.

Number of days after mating	Light mare ¹			Heavy mare ²		
	Results of immunoassay		Accuracy, percent	Results of immunoassay		Accuracy, percent
	Number of tests	+		-	Number of tests	
<29	1	0	0	12	0	12

¹ Light mare: Thoroughbred, Arab, Anglo-arab.

² Heavy mare: Percheron, Breton.

liquids in the upper layer were taken with a pipette, neutralized, and subjected to the haemagglutination test. Test samples prepared from pregnant mares' serum showed positive reaction, i.e., showed no agglutination of blood cells. Whereas, test samples from non-pregnant mares' serum exhibited negative reaction, that is, exhibited agglutination of blood cells.

EXAMPLE 3

To each 2 ml of serums of pregnant and non-pregnant mares, each 0.6 M metaphosphoric acid solution was added, well shaken, and thereafter either centrifuged or left standing. The obtained supernatant liquids were assayed in the manner similar to the procedure described in Example 1. The test samples from pregnant mares showed positive reaction, and those from non-pregnant mares, negative reaction.

However, when the above metaphosphoric acid solution was left to stand for a week and thereafter used in

55 What is claimed is:

1. In a method of diagnosis of pregnancy of a mare comprising mixing a test sample prepared from blood, plasma or serum containing pregnant mare serum gonadotrophin but substantially no proteinous impurities with antiserum against pregnant mare serum gonadotrophin; mixing the resultant solution with blood cells sensitized with pregnant mare serum gonadotrophin; and allowing the solution to stand to perform the haemagglutination inhibition reaction test, the improvement which comprises preparing the test sample in a liquid state by (1) adding sulfosalicylic acid to blood, plasma, or serum of the mare to be diagnosed at a concentration ranging from 0.2 to 1.2 m-mol based on 1 ml of serum and in an amount of 0.5 to 2 volume times the serum; (2) separating the resultant precipitate; (3) recovering the supernatant liquid, and (4) neutralizing the recovered supernatant liquid with an alkali to a pH within the range of 3 to 9.5.
